UNITED STATES PATENT OFFICE

2,598,567

HEATING DEVICE FOR ELECTRIC
DISCHARGE TUBES

Pierre Lemaigre-Voreaux, Paris, France, assignor
to Societe Anonyme pour les Applications de
l'Electricite et des Gaz Rares-Etablissements
Claude-Paz et Silva, Paris, France

Application January 11, 1949, Serial No. 70,170
In France February 13, 1948

2 Claims. (Cl. 315—49)

1

This invention relates to improvements in electric discharge tubes filled with rarefied gas and metallic vapor in which the current of the discharge includes a unidirectional component.

It is well known, for instance, that when a fluorescent lamp filled with rarefied gases and mercury vapor, designed for working on alternating current, is used on direct current without switching off for several periods of ten hours, it practically no longer has a lighting effect over a portion of its length beginning at its anodic extremity and extending over a length that, the longer the lamp and the larger the diameter, will be all the greater. This drawback is caused by the phenomenon known as cataphoresis that decreases progressively the homogeneousness of the gaseous filling of the fluorescent lamp, and, in a general way, of the discharge tubes containing at one and the same time at least one rare gas and one metallic vapor and in which more current flows in one direction than in the other.

The principal object of the invention is to provide electric discharge tubes in which the whole length of the positive column emits substantially evenly the desired radiation even when they work for a very long time, without switching off, on a current including a unidirectional component.

An important feature of the invention relates to the use of the heat originating in a resistor used for ballasting the tube, for heating a certain length of this tube on the side of the "cathode," this length, measured from the faraday dark space, being at least equal to a tenth of the length between electrodes, but not extending appreciably beyond a point situated at a distance from the "anode" equal to 5 times the diameter of the tube and even, preferably, to 10 times this diameter. Said "cathode" and said "anode" may have the same structure, but that electrode will here be termed "cathode" which, due to the unidirectional component of the current, plays the part of a cathode more than of an anode, the "anode" being the other electrode. When the feed current is purely unidirectional, the "cathode" plays only the part of a cathode and the "anode" only the part of an anode.

It has been found that the discharge tubes employed with this device remain luminous over the whole length of their positive column. The heated area must not extend too near the anode since then the dark anodic area reappears; a length equal to 5 times the diameter of the tube may be prescribed as a minimum for the non-heated anodic length. Preferably, the heated length extends over all the length of the tube,

2

except the "cathode" and its immediate neighborhood that are heated by the cathodic drop, and stops at a distance from the "anode" equal to about 10 times the diameter of the tube.

5 This heating may not be, besides, so strong as to prevent the condensation of the mercury in the heated area, since this condensation proves by itself no drawback from the point of view of cataphoresis. The exact limits of length of a 10 given type of tube that it is necessary to heat depend, among others, on the sizes of the tube, on the gaseous filling, on the design of the electrodes, and on the form of the discharge current when the tube is traversed by an undulatory current; that is why no general rule can be 15 given. These limits are, on the other hand, found easily by trials lasting for several periods of ten hours, carried out on a small number of tubes of this type. Some numerical examples are given 20 later on.

Other objects and advantages of the invention will become apparent as the description proceeds.

Referring to the drawing:

Figure 1 is a sectional view of a heating device 25 embodying the invention, on the line 1—1 of Figure 2.

Figure 2 is a sectional view, on the line 2—2 of Figure 1.

The lamp 3 is of a standard model, started by 30 preheating its thermoemissive electrodes that are heated by the discharge during working; these electrodes 10, 11 are 52 centimetres apart and are identical, the lamp being of a model intended for working normally on alternating current. This 35 lamp has an internal diameter of 3.5 centimetres and it is supported by the two caps 4 inserted in sockets 5 forming portion of a wireway 6 that encloses the resistance 7 constituting a part for ballasting the discharge. The distance between 40 these sockets is 58 centimetres. The lamp takes 30 watts and it is fed by a 110 volts, direct current network; its starting by preheating is ensured by the relay 8 housed in the wireway; the relay 8 comprises, as is known, for instance a 45 reactance and a glow switch with bimetallic electrodes mounted in series, not shown. The envelope of this lamp contains argon with a pressure of 3.5 mm. and a small drop of mercury. Its operating current and voltage are respectively 0.5 amp. and 57 volts.

The value when warm of the ballasting resistance is 80 ohms. This resistance is housed in the portion of the wireway situated above the electrode 10 connected to the negative pole of the 55 supply, therefore playing the part of cathode.

The wall of the wireway situated between this resistance and the lamp is drilled with holes 9 and the resistance extends over a length of 17 centimetres, starting straight over the cathode. As the distance between the latter and the faraday space is 2 centimetres, the heated portion of the tube is equal to 0.3 time the length between electrodes; the heated portion finishes at 35 centimetres from the anode 11, therefore at 10 diameters from this electrode.

For a lamp of similar construction but of 118 centimetres of length between electrodes and 110 volts operating voltage, a length of 83 centimetres from the cathode is heated.

What I claim is:

1. In combination, an electric discharge tube comprising an envelope filled with rarefied gas and metallic vapor and two main electrodes, a "cathode" and an "anode," the distance between the "cathode" and the "anode" being longer than eight-times the diameter of the envelope, a source of electric current for said tube, and ballasting means connected between said source and said tube, and comprising a heating resistor located close to the envelope of said tube, said resistor extending along said envelope at least between, on one side, the faraday dark space of the cathode of said tube when said tube is being supplied with electric current by said source through said ballasting means, and, on the other side, a point of said envelope situated at a distance from said dark space equal to at least one tenth of the length between said "cathode" and said "anode," and to at least twice the diameter of said envelope but not extending appreciably beyond a point situated at a distance from said "anode"

equal to five times the diameter of said envelope.

2. In combination, an electric discharge tube comprising an envelope filled with rarefied gas and metallic vapor and two main electrodes, a "cathode" and an "anode," the distance between the "cathode" and the "anode" being greater than thirteen times the diameter of the envelope, a source of electric current for said tube, and ballasting means connected between said source and said tube and comprising a heating resistor located close to the envelope of said tube, said resistor extending along said envelope at least between, on one side, the faraday dark space of the cathode of said tube when said tube is being supplied with electric current by said source through said ballasting means, and, on the other side, a point of said envelope situated at a distance from said dark space equal to at least one tenth of the length between said "cathode" and said "anode," and to at least twice the diameter of said envelope but not extending appreciably beyond a point situated at a distance from said "anode" equal to ten times the diameter of said envelope.
